UNITED STATES PATENT OFFICE.

CHARLES E. GODLEY, OF YPSILANTI, MICHIGAN, ASSIGNOR, BY MESNE ASSIGNMENTS, TO C. M. HALL LAMP COMPANY, A CORPORATION OF MICHIGAN.

LAMP-FOCUSING DEVICE.

Application filed September 16, 1926. Serial No. 135,973.

My invention relates to focusing devices of the general class employed on automobile headlights for adjusting the lamp socket longitudinally and for moving the socket in a vertical plane so as to adjust the height of the lamp bulb filament with respect to the axis of the reflector of the lamp.

Generally speaking, my invention aims to provide a lamp focusing arrangement in which the lamp socket extends slidably through a perforation and is adapted to rock upon the wall of the perforation; and in which the rocking of the socket is effected through cam means; aims to provide two independent adjusting means arranged so that an equal adjustment of both in the same direction will effect only a longitudinal sliding of the socket, while an adjustment of only one of these means (or a differential adjustment of both of these means) will rock the socket about the perforation wall; and aims to provide a connecting element associated with one of these means and arranged so as to be substantially rigid longitudinally of the socket while permitting a rocking of the socket.

Further and more detailed objects will appear from the following specification and from the accompanying drawings, in which

Fig. 1 is a fragmentary central, vertical and longitudinal section through an automobile headlight equipped with an embodiment of my invention in which the longitudinal adjusting movement is transmitted to the socket through an approximately straight resilient strip, showing the parts positioned for holding the lower filament of a two-filament lamp bulb on the axis of the reflector.

Fig. 2 is a section similar to Fig. 1, but showing an embodiment in which the longitudinal adjusting movement is transmitted through an S-shaped flat spring, showing the parts positioned for raising the lower filament above the axis of the reflector.

Fig. 3 is a fragmentary plan view, taken from the line 3—3 of Fig. 1.

Fig. 4 is a perspective view of the slideable yoke of Figs. 1 and 2.

Fig. 5 is a perspective view of the bracket

secured to the rear end of the socket of Fig. 1, which bracket has its rearwardly directed arm elongated in the embodiment of Fig. 2.

Fig. 6 is a perspective view showing the rear end portion of the shell of the socket before the bracket of Fig. 5 is secured to it.

Fig. 7 is a rear elevation of the central portion of the reflector.

In the drawings, Fig. 1 shows lamp parts including a portion of a reflector 1 spaced forwardly from the back 2 of the lamp casing. The reflector has at or near its center a perforation 3 slightly larger in diameter than the diameter of the shell 4 of the socket which holds the usual lamp bulb 5, and the perforation has at each side a lateral extension 3a for slidably housing one arm 6 of a yoke, which yoke forms the cam member of my focusing device. The two yoke arms have aligned cam slots 7 which are inclined with respect to the parallel upper and lower edges of the yoke arms, and the socket shell 8 has a pair of diametrically opposite nubs 8 formed on it. Each of these nubs projects into one of the cam slots and corresponds in diameter to the width of that slot, so that the nubs are slidable in the slots and also fulcrum the socket on the yoke. In assembling the parts, the arms of the yoke are first sprung apart to permit the entry of the nubs into the cam slots, after which the socket and the yoke arms are slid through the perforation in the reflector so that the walls of the lateral recesses or perforation extensions 3a not only support the yoke slidably but also hold the yoke arms interlocked with the said nubs.

To slide the yoke longitudinally, I provide a screw 9 which extends through the back of the casing and which is threaded through a suitable part of the yoke, such as the doubled lug 10 of Fig. 4. Then I also provide a second screw 11 extending through the back of the casing and I connect this to the socket shell 4 by connecting elements which include a flat strip 12 of resilient metal. In Fig. 1, I am showing a bracket having a horizontal arm 13 riveted to the forward end of this resilient strip and having a vertical arm 14 secured to the rear end 4a of the socket.

This socket end here has a tubular and non-circular extension 4^b (through which the usual wires enter the socket shell), which extension is slid through a correspondingly shaped perforation 15 in the bracket arm 14 (see Fig. 5) and is then flared out to clinch the said bracket arm to the socket shell.

The rear end of the resilient strip 12 is riveted to a horizontal arm 16 of a nut 17 which is threaded upon the second screw 11, and this arm 16 preferably extends in approximate alinement with the bracket arm 13. A compression spring 18 is interposed between the nut 17 and the back 2 of the casing so as to press the nut (and hence the screw 11) forwardly, thereby taking up any lost motion in the nut and also holding the head of the screw 11 against the rear face of the casing. Hence the spring 18 effectively causes the screw 11 to be swiveled to the casing and also holds the screw with its axis extending at right angles to the adjacent part of the casing back 2. Since the screw 11 is thus held in a fixed position and while the perforation extensions 3^a prevent the socket shell from rotating, and since the bracket at the rear of the socket is fastened to the shell, the angle-sectioned nut and the resilient strip cooperate in holding this strip substantially in a fixed plane and the strip also prevents the nut 17 from rotating on the screw 11. Hence no auxiliary parts are required for retaining the several elements of my focusing device in operative relation to each other.

With the parts thus assembled, a purely longitudinal adjusting movement of the socket (and hence of the lamp-bulb) is readily obtained by rotating each of the screws 9 and 11 in the same direction and to the same extent, as for example by turning each screw a quarter turn to the right or to the left. (Both screws preferably have the same pitch so as to insure this equality of longitudinal movement for the yoke which is moved by the lower screw 9 and for the socket shell which is connected to the upper screw 11.) Hence the needed adjustment of the filament longitudinally of the reflector can easily be made even by an inexperienced user.

Then the required vertical adjustment can be made by rotating only the lower screw 9, thereby sliding the yoke with respect to the socket so that the engagement of the cam slot with the nubs on the socket will rock the socket on the wall of the perforation 3 so as to raise or lower the lamp filament according to the direction in which the yoke is slid. For example, with the desired position of the lower lamp filament longitudinally of the reflector secured as in Fig. 1, a forward sliding of the yoke by merely rotating the (right-hand threaded) lower screw 9 in a counter-clockwise direction will

raise the lamp filaments to a position such as that of Fig. 2.

During these adjusting movements, the resilient strip 12 affords a substantially rigid connection between the screw-actuated nut 17 and the bracket on the socket shell, but this strip will bend to allow for the rocking of the socket.

Besides being cheaply and easily manufactured, my here presented focusing device 75 also is advantageous in its assembling, since all of its parts (except the guiding portion of the reflector) can be assembled initially on the casing, after which the reflector is slid into position over the socket and the so arms of the cam member which I have here shown as a yoke. Likewise, the removal and replacing of the reflector is unhampered, as no auxiliary parts are fastened to it.

On short focus reflectors I desirably form 85 the part adjacent to the perforation into a rearwardly extending tube 20 so as to dispose the perforated part behind the main surface of the reflector, thereby accommodating a lamp socket of the usual length. 90 However, I do not wish to be limited to this, nor to the use of a cam member in the form of a yoke, nor to other details of the construction and arrangement here described, since many changes might obviously be made without departing either from the spirit of my invention or from the appended claims.

For example, instead of having the bracket arm 13 and the nut arm 16 disposed substantially in alinement with each other and connected by a relatively long strip which is substantially straight, I may elongate one of these arms and dispose the arms out of alinement with each other. Thus, Fig. 2 100 shows an embodiment in which the arm 13^a of the bracket on the socket extends above the arm 16^a of the nut and in which these arms are connected by an S-shaped spring 21 of such a thickness of metal as to be substantially unyielding longitudinally of the said arms.

Fig. 2 also shows a spring washer 23 interposed between the back 2 of the lamp casing and a pin 24 extending transversely 115 through the upper screw 11, so that the said pin and washer prevent the screw 11 from sliding rearwardly while the engagement of the head of the screw with the said back of the casing prevents a forward sliding of this screw. Hence the screw 11 is effectively swiveled upon the casing back through which it extends, just as the same screw in Fig. 1 has a similar effective swiveling connection through the action of the spiral compression spring 18.

I claim as my invention:

1. In a lamp, a reflector having a perforation, a casing having its back spaced rearwardly from the reflector; a cam member 130

- and a socket both extending slidably through the perforation, the socket being adapted to rock in a vertical plane upon the wall of the perforation; cam means operatively interposed between the socket and cam member for causing a relative sliding thereof to rock the socket with respect to the carrier; adjustable means connecting the cam member with the back of the casing for sliding the socket with respect to the reflector, the last named means including a resilient member permitting a rocking of the socket upon the wall of the perforation, the resilient member being so formed and arranged as to make the last named means substantially rigid longitudinally of the axis of the reflector; and independent adjustable means for sliding the cam member with respect to the reflector.
2. In a lamp, a reflector having a perforation, a casing having its back spaced rearwardly from the reflector, a lamp socket extending slidably through a portion of the perforation and adapted to rock in a vertical plane on the walls of the said portion of the perforation; a cam member having a pair of arms extending slidably through other parts of the perforation at opposite sides of the socket, the said arms having alined cam slots disposed behind the said perforation, and the socket having trunnions housed respectively by the said slots and slideable in the slots; means connecting the back of the casing with the cam member for sliding the cam member with respect to the reflector; and means connecting the back of the casing with the socket for sliding the socket with respect to the reflector, the last named means being substantially rigid longitudinally of the reflector but including a resilient member arranged to permit a rocking of the socket about the walls of the first named perforation portion.
3. In a lamp, a reflector having a perforation, a casing having its back spaced rearwardly from the reflector, a lamp socket extending slidably through the portion of the perforation and adapted to rock in a vertical plane on the walls of the said portion of the perforation; a cam member having a pair of arms extending slidably through other parts of the perforation at opposite sides of the socket, the said arms having alined cam slots disposed behind the said perforation, and the socket having trunnions housed respectively by the said slots and slideable in the slots; an adjusting screw extending through the back of the casing and threadedly connected to the cam member for sliding the cam member with respect to the reflector, the mounting of the screw on the casing back cooperating with the engagement of the said other perforation parts by the cam member to prevent a rocking of the cam member upon the reflector; a second adjusting screw extending forwardly through the back of the casing, and a resilient connection between the second screw and the socket, the resilient connection being substantially rigid longitudinally of the second screw so that a rotation of that screw slides the socket with respect to the reflector; the resiliency of the said connection permitting the socket to rock on the reflector upon a relative sliding movement of the socket with respect to the cam member.
4. In a lamp, a reflector having a perforation provided with a pair of laterally opposite enlargements, a casing having its back spaced rearwardly from the reflector, a socket extending slidably through the perforation and adapted to rock in a vertical plane upon the parts of the perforation between the said enlargements, the socket having a pair of laterally projecting trunnions respectively behind the two enlargements; a cam member having a pair of arms extending at opposite sides of the socket respectively through the said enlargements, each arm having a cam slot slidably housing one of the said trunnions; an adjusting screw extending forwardly through the back of the casing and threaded through a part of the cam member for sliding the cam member longitudinally of the reflector; another screw extending forwardly through the back of the casing, and a connection fast upon the socket and threaded upon the last named screw whereby the last named screw slides the socket longitudinally of the reflector and of the cam member; the said connection being substantially rigid longitudinally of the first named screw but including an element arranged to permit a tilting of the axis of the socket with respect to the axis of the first named screw by adjustment of the last named screw, so as to allow a relative sliding of the socket and carrier to rock the socket on the reflector through the action of the cam slots on the said trunnions.
5. In a lamp, a reflector having a perforation, a casing having its back spaced rearwardly from the reflector, a cam member extending slidably through the perforation in the reflector, an adjusting member extending through the back of the casing and cooperating with the wall of the said perforation to support the cam member continuously on axial alinement with the reflector, the adjusting member being operable from outside the casing to slide the cam member with respect to the reflector; a lamp socket supported jointly by the wall of the said perforation and by the cam member, the lamp socket being adapted to rock in a vertical plane with respect to the socket and the said perforation being formed to prevent rocking of the cam member in a vertical plane with respect to the reflector; a second adjusting member connecting the back

of the casing with the socket and operable independently of the aforesaid adjusting member for sliding the socket with respect to the reflector; the socket and the cam member having interengaging formations operating with a cam action for causing a relative sliding of the socket and the cam member to rock the socket on the wall of the said perforation.

6. A lamp construction as per claim 5, in which the adjusting means connecting the back of the casing with the socket include a resilient strip formed for normally holding the socket coaxial with the reflector.

Signed at Detroit, Michigan, September 15, 1926.
